UNITED STATES PATENT OFFICE.

CLARENCE T. McDONALD, OF CHICAGO, ILLINOIS, ASSIGNOR TO CHICAGO FUSE MFG. CO., OF CHICAGO, ILLINOIS, A CORPORATION OF ILLINOIS.

INCLOSED FUSE.

1,379,114.

Specification of Letters Patent.

Patented May 24, 1921.

Application filed November 21, 1918. Serial No. 263,472.

To all whom it may concern:

Be it known that I, CLARENCE T. McDONALD, a citizen of the United States, residing at Chicago, in the county of Cook and State 5 of Illinois, have invented certain new and useful Improvements in Inclosed Fuses, of which the following is a specification.

It is well known that the operation of an inclosed fuse on heavy overload is somewhat 10 analogous to an explosion due to the fact that the fusible element, or a portion thereof, melts and is converted into gas under high pressure. This gas exerts an enormous strain upon the casing and is apt to burst 15 the latter and injure workmen or apparatus nearby. The principal objects of this invention are to provide a novel construction by which the pressure in the fuse casing caused by the blowing of the fuse will be less 20 than it is in ordinary refillable fuses of the air chamber type in common use, and by which the fusible element will be caused to melt simultaneously over a relatively large area at the mid-portion of the fuse so as to 25 effect an unusually wide break in the circuit all at once and thereby prevent arcing. I have discovered that these results may be accomplished by covering or inclosing a section or area of the fusible element having 30 uniform cross-section with a coating or envelop of insulating material so located that the ends of the covered section will be spaced from the terminals or mounting means in the casing so as to leave exposed the inter- 35 mediate portions of the fusible element which extend between the covered section and the terminals. The insulating envelop acts to retard the melting and rupture of the middle point of the section of the fusible ele- 40 ment which it covers, and causes the whole covered section, or a relatively long section of the central portion of the element, to be brought to a state of fusion at the same time, thereby effecting a break in the ele- 45 ment over a large area all at once.

In the accompanying drawings, Figure 1 is a longitudinal central section through an inclosed fuse embodying my invention. Fig. 2 is a transverse section taken in the 50 plane of line 2-2 of Fig. 1, and looking in the direction of the arrows. Fig. 3 is a perspective view of the fusible element as it appears before being mounted in the casing. Fig. 4 is a transverse section through the 55 fuse element in the plane of line 4-4 of Fig. 3.

The casing of the fuse, and the means for securing the fuse element may be of any common or preferred construction. Inclosed or cartridge fuses now on the market 60 are of two general types, one known as the knife blade type (an example of which is shown in my prior Patent No. 1,311,661), the other type being known as the ferrule type. My invention is adapted for either of 65 said types. The exemplary embodiment shown in the drawing is a fuse of the so-called ferrule type, and the ends of the fuse element are removably mounted so that the fuse element may be replaced by the user 70 when disrupted. This illustrative embodiment comprises a tubular shell 5 of insulating material, two metallic heads 6 secured on opposite ends of such shell, each head having therein an integral transversely dis- 75 posed segmental web 7 and a merging arcuate shoulder 8, two removable segmental disks 9 cooperating with such webs and shoulders to provide slots through which the ends of the fusible element 10 project, said 80 ends being bent angularly against the outer faces of said disks, and two plugs 11 screw-threaded into the outer ends of said heads and clamping the bent-over ends of the fuse element between the plugs and the disks. 85 The plugs and disks are readily removable so as to permit of removal of the fuse element 10 after melting, and replacing of a new element. This construction of the casing and fuse mounting means is described 90 and claimed in my copending application Serial No. 219,597 filed February 28, 1918. Any other desired form of fuse case and mounting means may be employed.

The fuse element 10 is preferably in the 95 form of a flat strip of fusible metal of uniform width and cross-sectional area throughout its central portion so that the current-carrying capacity of such central portion is substantially the same at all points. A 100 portion of the fuse element preferably located at the middle thereof is covered or inclosed by a suitable protective film 12. A coating of paint is the form of inclosure or covering preferred, an insulating paint of 105 a character which will not attack or chemically react on the fusible metal being employed. The ends of the covering material are spaced a material distance from the terminals or supporting means for the ends of 110 the fuse element.

Without the covering material, the fuse

element would become hottest and would melt and rupture first on a line extending across the element at about its middle point, and the degree of heat of the element would 5 be gradually lower from such median line toward the ends of the element because of the median line being located farthest from the terminals which act to radiate the heat. Beginning with the melting and rupture 10 along the said median line, the element would then melt in opposite directions away from such median line, with the result that an arc would be formed through the gap or rupture and the arc would be sustained and progressively lengthened until the gap increased to such an extent as to break the arc. This 15 arcing produces intense heat and builds up tremendous pressure of the gases within the casing tending to burst the casing.

20 When the mid-portion of the fuse element is covered with a non-conducting material, in accordance with my invention, the fuse element is not melted and ruptured first at the transverse median line, but the entire 25 covered mid-portion, or a relatively long section of such mid-portion of the element is simultaneously melted or consumed in the process of blowing.

A fuse constructed in accordance with my 30 invention is particularly valuable under heavy overloads and short circuit conditions, since arcing within the casing, as above described, is most vicious under such conditions, resulting in the generation of excessive pressure within the casing and danger of bursting 35 of the casing. My invention provides a fuse wherein the fusible element is melted and ruptured over a wide area at the same instant thereby creating a wide gap in the 40 circuit and effectively preventing serious arcing.

I have found by actual tests that the bursting strain in the casing caused by the blowing of this fuse is less than it is when an ordinary 45 fuse strip is used, under conditions otherwise identical, and that casings which would be bursted by using an ordinary fuse strip will not be injured when employed with my fuse element.

50 I claim as my invention:

1. An inclosed fuse comprising a casing, a fusible element in the form of a flat strip of fusible metal of uniform width and cross-section throughout its middle portion, so 55 that its current carrying capacity is substantially the same at all points throughout such middle portion, means for mounting the ends of said element in the ends of said casing, and a coating of paint applied to and surrounding a section of said element and spaced inwardly from the ends of said element and from the means for mounting said element to leave exposed the intermediate portions of the element between said coating 60 and said mounting means.

2. An inclosed fuse comprising a casing, a fusible element therein, means for mounting the ends of the said element, and a coating of paint applied to and surrounding a section of said element and spaced inwardly 70 from the said means for mounting the element, thereby leaving exposed portions of the element between the covered portion and the portions secured to the mounting means.

3. An inclosed fuse comprising a casing, 75 terminals carried at the ends of said casing, a fusible element extending through said casing and connected to said terminals, and a protective film applied to and surrounding an intermediate portion of said element 80 spaced from said terminals and leaving exposed the end portions of said element adjacent to said terminals.

4. A fusible element for inclosed fuses having a section thereof provided with a 85 thin protective coating or film with exposed sections of substantial length on opposite sides of the coated section whereby said coated and uncoated sections coact upon the passage of an excessive current through the 90 element to produce a wide break.

5. A fusible element for inclosed fuses having a section thereof provided with a thin protective coating or film with exposed sections of substantial length on opposite sides 95 of the coated section, the distance between the remote ends of the coated section being less than the distance between the points of attachment of the element to the terminals of the inclosed fuse casing in which the element is designed to be used whereby said coated and uncoated sections coact, upon the passage of an excessive current through the 100 element, to produce a wide break.

6. An inclosed fuse comprising a casing 105 having terminal means at its ends to secure a fusible element, a fusible element extending through said casing and attached to said terminal means, and a covering material applied to and surrounding an intermediate 110 portion of said element spaced from said terminal means and leaving exposed the end portions of said element adjacent to said terminals, said covering material acting to cause simultaneous fusion of the section of 115 the element covered by said material, and said material being relatively thin so that it will be disrupted into fine bits along with the metal of said element when the latter reaches a state of fusion.

7. An inclosed fuse comprising a casing 120 having terminal means at its ends to secure a fusible element, a fusible element extending through said casing and attached to said terminal means, and a covering material applied to and surrounding an intermediate 125 portion of said element spaced from said terminal means and leaving exposed the end portions of said elements adjacent to said terminals, said covering material affecting 130

the radiation of heat from the mid-point of said element thereby preventing premature fusion of said mid-point and causing the entire portion of said element covered by said material to come to a state of fusion at practically the same time, thereby effecting a disintegration or vaporization of the entire covered portion of the element simultaneously and causing a wide break in the ele-

ment so as to prevent arcing, the said covering material being relatively thin so that it will itself be disintegrated and broken up into fine bits when the covered portion of the element is destroyed by fusion and vaporization.

In testimony whereof I have hereunto set my hand.

CLARENCE T. McDONALD.
